INDICATING-REGISTER FOR LOCKS.

1,243,826.

Specification of Letters Patent. Patented Oct. 23, 1917.

Application filed September 2, 1913. Serial No. 787,703.

To all whom it may concern:

Be it known that I, WILLIS S. FARNSWORTH, a citizen of the United States, residing at San Francisco, in the county of 5 San Francisco and State of California, have invented certain new and useful Improvements in Indicating-Registers for Locks, of which the following is a description.

My invention belongs to that general class 10 of devices known as locks, and more particularly to a lock provided with means for automatically registering and indicating the operation of the same. It is particularly adapted to coin controlled locks for registering the successive operations of the same, and consequently indicating the total number 15 of coins deposited. As shown, it is especially desirable for use in connection with the coin controlled and key actuated lock shown in my U. S. Letters Patent No. 1,076,822, granted October 28, 1913, in which device the latch bolt is prevented from being operated until the deposit of a proper token, and which is so constructed as to admit of 20 the key being withdrawn or thrown to locking position only on the deposit of a proper coin or token. The use of the device herein described, however, is not limited to devices of that particular type, as the same may be 25 applied to practically any lock, whether it be a key or combination. For the purpose of making the present invention clear, I shall describe it as applied to the type of lock illustrated in my pending application 30 above mentioned and partially illustrated herein.

The invention has among its objects the production of a device of the kind described 35 that is simple and compact, attractive, efficient, durable, accurate, and satisfactory, that may be applied to locks already installed, and that cannot be easily tampered with or manipulated to fraudulently change the reading of the same.

To this end my invention consists in the 40 novel construction, arrangement and combination of parts herein shown and described, and more particularly pointed out in the claims.

In the drawings, wherein like reference 45 characters indicate like or corresponding parts,

Figure 1 is a front elevation of the complete lock and register;

Fig. 2 is a sectional view taken substantially on line 2, 2 of Fig. 4;

Fig. 3 is substantially a view in elevation of a portion of the mechanism with the casing and dials removed;

Fig. 4 is a sectional view substantially on 60 line 4, 4 of Fig. 1;

Fig. 5 is a perspective view of the pawl member;

Fig. 6 is a perspective view of the pawl carrying member;

Fig. 7 is a sectional view taken substantially on line 7, 7 of Fig. 4;

Fig. 8 is a view similar to a portion of Fig. 2, showing the parts in changed positions;

Fig. 9 is a view similar to Fig. 2 with the dial 35 removed;

Fig. 10 is a front elevation of another form of my device;

Fig. 11 is an enlarged view of a portion 75 of the same, showing the registering dial, and the cover of the casing removed, and

Fig. 12 is a sectional view taken substantially on line 12, 12 of Fig. 11.

As before mentioned, I have illustrated in 80 the drawings a form of lock to which the registering device is particularly applicable and desirable. This device is not shown complete in all details, the understanding of the complete lock being had by reference 85 to my patent mentioned. The lock shown comprises a plate 1, which is secured to a part 2 of the door frame in proximity to the door 3. It is immaterial whether the lock be placed upon the door or upon the 90 door frame, except in coin or token controlled locks it is more convenient to place them upon the frame so that the coin chutes may be simplified in construction, particularly where a common till for receiving the 95 tokens is employed. The lock shown is controlled by a key 4, the well known pin lock type of lock being illustrated, which is provided with a key cylinder 5, which extends into the tubular casing 9, 10 (see Fig. 4.) The 100 lock is provided with a suitable coin chute (not shown) and an opening 6, through which the tokens may be inserted. In this particular device embodying my improvements, the key 4 is maintained and locked in 105 the cylinder 5, and cannot be withdrawn or the latch bolt thrown to operative position until a token, such as a coin, is dropped in

the slot 6. The key may then be turned to lock the door and then be withdrawn. As the key, however, is thrown to locking position, the registering mechanism hereafter described, registers and indicates the same through the opening 7 in the registering mechanism casing 8. When it is desired to unlock the door 3, the key is inserted and the latch bolt thrown to unlocking position, 10 depositing the coin in the till, and at the same time the key is locked so that it cannot be again withdrawn without depositing another token. The registering mechanism is so arranged that it will only register when 15 the latch bolt is operatively actuated, that is, only when a coin is deposited. By this means the number of tokens deposited in the till may be easily checked. Locks of this type are particularly adapted for package 20 checking lockers for use in public places, in which one may place an article desired to be checked, deposit the required token, lock the locker, taking the key check, that is, the key is the check. When ready to 25 claim the article checked, the key is inserted and the locker unlocked, and at the same time the key is again locked in the lock until another token is deposited.

As most clearly shown in Figs. 4 and 7, 30 12 is the latch bolt, which is arranged to be actuated by a tinger or part 11, carried by the rotatable cylinder 5. The latch bolt is carried by the support 17, and by the flanged side 16 of the lock plate 1, or in an equivalent manner. I have not considered it necessary to illustrate in detail the complete locking mechanism. Arranged on the locking cylinder 5 is a suitable rockable or partially rotatable member 18, which is connected by 35 screws 24, or the equivalent (see Fig. 3) passing through slots 23 to the coin controlling mechanism (not shown in detail). Arranged on the member 18 is a rockable or partially rotatable plate 19, which is preferably flanged as at 20 to provide a collar, and provided with a tongue 21, which engages a pin 22 secured to the plate 1. Mounted on the plate 19 is a plate 25 having an extension 26, formed with a lug or flange 40 27, and provided with a pin 28. Mounted over the plate 25 is a suitable washer 30, and over this is mounted a dial member 31 (see Figs. 4 and 9.) The dial member 31 is provided with teeth, or that is with 45 shoulders 32 about its circumference, one shoulder 33 being greater or deeper than the others. Arranged next to dial 31 is a washer 34, and over this is arranged a dial member 35, which is notched as at 36, so as to clearly 50 show the characters on the dial 31, and form teeth for the pawl for actuating the same. The flange 20 on plate 19 forms a stationary bearing for the dial members.

The lug or flange 27 on the extension 26 55 of the plate 25 extends down into a notch

or recess in the edge of the plate 18, and is adapted to coöperate with either of the faces 18' or 18², as will be more clearly explained in the operation of the device. On the pin 28 is arranged a pawl 37 (see Fig. 5) which 70 is provided with the tip or end 39 formed to engage with the shoulders 32 on the dial 31, and with an end 41 arranged to engage with the shoulders on the dial 35. It is also formed with a part 40, which is substantially 75 the same thickness as the washer 34, and which extends between the two dials, and guides the pawl. It will be noted by referring to the figure above referred to, that the end at 39 on the pawl extends slightly 80 beyond the lower face of the end at 41. The end at 41 does not engage the shoulders on the dial 35 and actuate the same at every movement of the pawl, but only after each complete rotation of the dial member 31. 85 Each time that the shoulder 33 is engaged by the end 39 of the pawl, the pawl drops into the nick a sufficient distance to permit the end 41 to engage with one of the shoulders on the dial 35, so that the dial 35 is at that 90 time moved sufficiently to bring the next or succeeding characters before the opening 7 in the casing 8. The pawl is normally maintained in operative position by a spring 38, or its equivalents for the purpose. 95

As the plate 25 is rocked by the engagement of the face 18', when the cylinder 5 is moved by the key, the pawl 37 is moved to engage a new tooth on the dial 31. When the key is turned to lock the door, or in the opposite direction, the shoulder 18², engaging with the extension or lug 27, moves the plate 25 and carries the pawl and dial to advance one character. It will be noted that a certain initial movement is permitted of 100 the key and cylinder before the shoulders 18² or 18' engage with the lug 27. This is lost motion, but it permits more characters to be placed on the dial, since the dial is not advanced as much as would be the case 110 if the plate 25 was secured to the part 18, or what is the same thing, the pawl carried by the part 18.

The dials are prevented from moving forward when the pawl is moved to take a new 115 bite, or that is, engage a new tooth on the dials, by the resilient pawl or locking member 42. This member, as most clearly shown in Figs. 3 and 7, is maintained in position by the pin 22 and its extended end 42', and 120 is provided with the two faces 42² and 42³, arranged to bear against the edges of the dial members. The part 42' (see Fig. 7) bears against the edge of the plate 25, and acts substantially as a friction brake, so that 125 it does not move until engaged by one or the other of the faces 18' or 18² with the lug 27. The casing 8 may be secured to the plate 1 in any desired manner, screws or bolts 45 being shown for the purpose. The opening 130

7 is also preferably covered with glass or the like to prevent tampering with the dials through the opening.

In operation, assuming that the parts are substantially as shown in Figs. 1, 2 and 3, when the key 4 is turned clockwise so as to throw the bolt 12, it being understood that a coin has been deposited in the slot 6, so that the key may be turned, the plate 18 is moved by the key so that the face 18² engages the lug 27 and moves the plate 25 and extension 26, carrying the pawl 37, and this moves the dial 31, to bring a new character at the opening 7. The key may then be withdrawn from the lock. When the key is re-inserted and turned to unlock the device or return the latch bolt to the position shown, the plate 25 and extension 26 is moved when the face 18² of the member 18 comes in contact with the lug 27, moving the pawl 37 where it will engage a new shoulder 32 when the key is again thrown to the locking position. In the particular coin controlled lock shown, the coin having been previously registered is at this time released and dropped into the till. Whenever the dial 31 is rotated to bring the shoulder 33 where it is engaged by the pawl tooth 39, the pawl 37 drops sufficiently to allow the tooth 41 to engage with the dial 35, so that as soon as the key is turned, that dial is moved one character. The same is repeated when the dial 31 has again made a complete rotation. While I have shown but two dials, it is, of course, obvious that there may be any number desired, and they may be connected to carry one from the other, similar to the carrying between the two dials described, or in any equivalent manner. Ordinarily, however, two dials are sufficient for the purpose, at least for illustrating the invention.

The construction shown in Figs. 10, 11 and 12 is slightly different, but in operation the results are the same. Referring to these figures, 1 represents the plate provided with the coin slot 6, the key cylinder 5, and key 4, which co-operate with the lock cylinder casing 9. In this device the casing 48, which is provided with a cover 49, is movable with the key and cylinder; that is, it rocks with the key cylinder 5. As shown, the casing part 48 is formed with a part 50, which is suitably connected with the coin controlled mechanism. The casing is secured to the cover 49, which is secured to the cylinder 5. Arranged within the casing is a plate 52, which is provided with a pin 57. Arranged adjacent the plate is a ratchet wheel 56, which is suitably connected to a dial member 53, bearing suitable characters upon its face. A co-operating dial 55 is provided with a ratchet wheel 56 at the back, and with characters upon its face. Carried by the pin 57 is a pawl or pawls 58, which are provided with parts 60 and 61, arranged to engage the ratchet gear 56 and 54 respectively. In this construction, the outer dial 55 makes one complete rotation for each time the inner dial moves one character, the carrying being 70 similar to the other construction, that is, by providing a somewhat deeper tooth or shoulder 56'. (See Fig. 11.) The casing, when the key is turned in one direction or the other, contacts with the extension 52, operating the pawl. Assuming that the parts are as shown in Fig. 11, when the key is turned clockwise, the casing engages with the face 52² of the extension 52, causing the pawl to move the dial 55 one character. When the 80 key is turned in the opposite direction, the pawl is brought to a position to engage a new tooth, the casing engaging the face 52² of the extension 52. The dials are prevented from moving backward by the resilient 85 member 63, which extends over the pin 62, as shown at Fig. 11, and is arranged to engage with the member 51 and act as a brake, as in the other construction. There may be two openings in the cover if desired so that 90 the dials may be read regardless of the position of the casing.

As was previously mentioned, the registering device is applicable for any type of lock, particularly a lock in which a part may be rocked, as is the cylinder 5. It may be used with or without the coin or token controlling mechanism, but is in most cases not required or desired where such mechanisms are not employed. It will be noted that the characters on the dials are in the form of letters rather than numerals, although the numerals, or the equivalent, may be used if so desired. The advantage of letters is that the public reading the dials cannot determine 100 the amount deposited in the till, so that the temptation of robbing the till is done away with. The letters may also be arranged in different ways on different registers, and a record of the register kept at the office, so 110 that even an employee cannot determine the reading of the registers without having access to the cards or records. This enables the auditor to secretly check the accounts of the lessee of the devices, or the one having 115 charge of the same. It might also be mentioned that in connection with the registering devices, means may be employed to co-operate therewith and record upon paper or the like the operations of the devices. This 120 is merely suggested, and is not illustrated. In the two forms of device illustrated, the dials are movable relative a fixed indicating point, to-wit, the opening through which the dials are seen. An obvious alternate 125 construction would be a fixed dial and one or more movable indicating points or pointers.

Having thus described my invention, it is obvious that various immaterial modifica- 130

tions may be made in the same without departing from the spirit of my invention; hence I do not wish to be understood as limiting myself to the exact form, construction, arrangement or combination of parts herein shown and described, or uses mentioned.

What I claim as new and desire to secure by Letters Patent is:

1. The combination in a lock, of a latch bolt, actuating means therefor, including a key, means for transmitting the movements of said key to the bolt, and means for registering the movements of said bolt, comprising a plurality of coöperating dials provided 10 with suitable characters thereon, an actuating pawl for said dials, a supporting member for said pawl, and means for rocking said supporting member at each turning movement of the key.
2. The combination in a lock, of a latch bolt, actuating means therefor, including a key, means for transmitting the movements of said key to the bolt, and means for registering and indicating the movements of said 15 bolt, comprising a plurality of coöperating dials provided with suitable characters thereon, an actuating pawl for said dials, a supporting member for said pawl, and means for rocking said supporting member at each 20 turning movement of the key after an initial movement of the key.
3. In a lock and in combination, a latch bolt, key operated actuating means therefor, a plurality of rotatable dials, each having 25 suitable characters thereon, a casing arranged about said dials and arranged to display a portion of the characters thereon, means for rotating said dials including a pawl common to all the dials, means connect- 30 ed with and coöperating with said bolt actuating means for positively actuating said pawl, after an initial movement of the latch bolt, and means for preventing backward rotation of the dials.
4. In a device of the kind described and in combination, locking mechanism including a latch bolt, actuating means therefor including key-controlled mechanism operatively connected with said locking mechanism, and means for registering the successive 35 movements of the locking mechanism, comprising a member operatively connected therewith, said member provided with a flange projecting from one face thereof, a 40 collar arranged on said flange and provided with means for preventing the movement thereof on the flange, a plate mounted on said collar and provided with means for operatively connecting the same with said member, a plurality of dials having suitable 45 indicating characters thereon and

mounted on said collar, one in front of the other, and a pawl carried by said plate and arranged to engage said dials, one of said dials having a portion cut away whereby the other dial will be engaged by the pawl at each complete rotation of the first mentioned dial.

5. In a device of the kind described and in combination, locking mechanism including a latch bolt, actuating means therefor including key-controlled mechanism operatively connected with said locking mechanism, and means for registering the successive movements of the locking mechanism, comprising a member operatively connected therewith, said member provided with a flange projecting from one face thereof, a collar arranged on said flange and provided with means for preventing the movement thereof on the flange, a plate mounted on said collar and provided with means for operatively connecting the same with said member, a plurality of dials having suitable indicating characters thereon and mounted 70 on said collar, one in front of the other, a pawl carried by said plate and arranged to engage said dials, one of said dials having a portion cut away whereby the other dial will be engaged by the pawl at each 75 complete rotation of the first mentioned dial, and means for yieldingly opposing the movement of said plate and preventing a reverse rotation of the dials, the outer dial having portions cut away whereby the characters 80 on the other dial are partially displayed.

6. In a device of the kind described and in combination, a latch bolt, actuating means therefor including key-controlled mechanism operatively connected with the bolt, and means for registering the operations of the lock, comprising a plurality of coöperating rotatable dials, each having suitable characters thereon, a single actuating pawl common to both of said dials, a fixed support for rotatably supporting said dials, one in front of the other, said actuating pawl arranged to engage one dial at each complete rotation of the other dial, a supporting member for said pawl mounted on said fixed support, means for rocking said supporting member and pawl, including a second rocking member operatively connected with the locking mechanism.

In testimony whereof, I have hereunto signed my name in the presence of two subscribing witnesses.

WILLIS S. FARNSWORTH.
